UNITED STATES PATENT OFFICE.

JOSEPH STUBBERS, OF COVINGTON, KENTUCKY, ASSIGNOR TO THE INCANDESCENT LIGHT & STOVE COMPANY, OF CINCINNATI, OHIO, A CORPORATION.

AIR-MIXING PIPE FOR VAPOR-BURNERS.

SPECIFICATION forming part of Letters Patent No. 764,159, dated July 5, 1904.

Application filed December 23, 1903. Serial No. 186,274. (No model.)

To all whom it may concern:

Be it known that I, JOSEPH STUBBERS, a citizen of the United States, residing at Covington, in the county of Kenton and State of Kentucky, have invented certain new and useful Improvements in Air-Mixing Pipes for Vapor-Burners, of which the following is a specification.

My invention relates to a device for mixing air with gas for burners. It is primarily intended to be used with gasolene-gas generators for supplying incandescent burners.

The object of my invention is, first, to employ the mixer with a supply - pipe which serves to deliver the carbureted gas to a large number of burners; second, to construct the mixing device so that it can be quickly and easily adjusted for the use of quite a number of burners and avoiding the necessity of regulating the device when one or two or three burners are turned on or off.

The features of my invention and mode of operation are fully set forth in the description of the accompanying drawings, forming a part of this specification.

In the accompanying drawings I have shown the mixer attached to the delivery-pipe of a gasolene-generator, the kind shown in Letters Patent No. 683,232, granted September 24, 1901.

Figure 1 is a side elevation, partly in section, of my mixer attached to the generator and service-pipe in position for use. Fig. 2 is an enlarged central burner-section, showing the mixer in elevation and in relative arrangement with the service-pipe. Fig. 3 is a section on line $x-x$, Fig. 2.

A represents a gasolene-gas generator; A', the generator-pipe.

40 B represents the needle - valve rod; b, the needle-valve for supplying gas to the mixer and service-pipe.

C represents the air-supply pipe, which is the preferred method of supplying the air to be mixed with the gas.

D represents the service or main gas-supply pipe.

a represents the mixing-tube. In the pre-

ferred form of construction the upper end of this tube is made larger than the lower. Said 50 pipe is supported so as to be revoluble, the lower end being projected into a circular opening on the air-pipe.

a' represents a collar fastened near the base of the pipe and serving as a vertical support 55 therefor. d represents a stem affixed to said collar, so that the pipe may be turned in its annular seat. The mixer-pipe projects up into the service-pipe and is supported in what may be termed a "stuffing-box" to prevent the 60 leakage of gas.

E represents the stuffing - box, which surrounds the mixer within the service-pipe and preferably constructed as shown in Fig. 2.

F represents a sleeve having a circular flange 65 e extending outwardly therefrom and provided with lugs e'. Upon this sleeve is mounted a sleeve-plate h, to which service-pipe D is fixed. This plate is held in position upon the flange of the sleeve F by a clamping-ring 70 G, which in turn is held in position by screws passing through the lugs e'. The inner face or periphery of the sleeve F is screw-threaded.

H represents a cylindrical cap having screw-threaded engagement with the sleeve F and 75 provided with an extended sleeve portion H' for supporting the mixer-pipe a, closely fitting said mixer-pipe and provided with an orifice I. Said cap H contains an outwardly-extending annular disk h', thence extending vertically down and thence flanging outwardly, as at h'', affording a handhold means for attaching and detaching the cap h.

g represents a packing for preventing the leakage of gas between the cap-sleeve and 85 mixer-pipe.

J represents a cup-shaped cap having screw-threaded engagement with the cap H for securing the packing g in position.

The mixer-pipe is provided with an orifice 90 K, (see Fig. 2,) which may be turned to register with the orifice I to form a free opening and exit at that point for the gas and air from the mixer-pipe into the service - pipe, or it may be turned to close said exit, in which position it is shown in Fig. 2.

Mode of operation: In the ordinary construction of service-pipes and burners it is usual to employ a mixing-tube with each burner. In the use of gasolene and gas generators where a building is to be lighted by service-pipes—say to support sixteen or eighteen burners—it has been found impossible hitherto to employ one mixing-pipe which would do the mixing properly for the entire range 10 of burners. It is also important to have the proper mixture of air and gas in order to get a perfect light. If too much air is mixed with the gas, the gas will not all burn. Consequently it escapes into the room, giving off 15 an odor as well as wasting the gas. If too little air is mixed with the gas, a good light will not be obtained. As the number of burners in use on the service-pipe are varied from time to time, it is also necessary to vary the 20 amount of air mixed with the vapor. It has been found difficult where the mixer is used at the base of the service-pipe to regulate the mixing of air with the increase or decrease of one or more burners. It has been found 25 by experience that increasing the length of the mixing-tube and in some cases increasing the size of the mixing-tube without increasing the length will increase the amount of air mixed with a given supply of gas. My 30 present method relates to the use of a single mixing-tube, but practically to change the effective length of the tube proportionately to the changed conditions by making a by-pass I K near the base of the service-pipe, so 35 as to escape a greater or lesser amount of gas directly into the service-pipe at this point instead of forcing the gas all through the entire length of the mixing-tube, at other times using the entire length of the mixing-tube, as con- 40 ditions require.

I have discovered by experience that the method of mixing air and gas shown and described can be quickly and readily adapted so as to properly mix air and supply with gas 45 any usual number of burners—say up to sixteen or eighteen, often employed on one service-pipe. The following are the conditions and means of regulation of such a mixing device: Say but three or four lights are to be 50 used. If now the straight or lower part of the mixing-tube is seven-eighths of an inch in diameter, it is too large to draw sufficient air into it by the force of the vapor when same is delivered from the needle-opening with a 55 pressure of about fifteen pounds to the square inch; but by lengthening the mixing-tube the entraining of the air is materially increased. I therefore close the by-pass I K. If now the burners are to be increased, say, up to about 60 ten, an additional amount of gas must be supplied, and if the entire length of the mixing-pipe is employed too much air will be entrained in with the gas—consequently a poor light and odor in the room; but by turning 65 the mixing-pipe so as to open partially or en-

tirely the by-pass I K the requisite amount of air-mixture can readily be obtained. If nearly the entire or all of the number of lights are to be used, of course an increased supply of gas is required, and the needle-valve will be 70 turned to give such supply. If nearly the entire amount of lights are on and the by-pass partially opened, too little air will be admitted to give a good light, because the mixing-tube is too small in diameter; but by closing the 75 by-pass I K and using the entire length of the mixing-pipe the requisite amount of air-mixture is obtained. Hence by this method any desired number of lights may be employed and a single mixer used and good lights ob- 80 tained.

It will be observed that the stem *d* serves as an indicator to show the position of the by-pass, and the attendant will quickly learn to adjust the by-pass to any change of conditions 85 required, and this index or stem is a very eligible adjunct of this invention. The use of the by-pass is, in effect, changing the efficient length of the mixing-tube and the equivalent of a telescopic tube, with means for actually 90 changing the length of such tube; but the form shown is simpler and just as efficient.

Having described my invention, I claim—

1. In combination with a service-pipe, an air-mixing tube supported and projecting 95 therein having a fixed mouth and provided with a by-pass within the service-pipe and means for regulating the by-pass, substantially as described.

2. In combination with a service-pipe, a 100 mixing-tube projecting into said pipe and provided with a by-pass within said pipe, means for securing and sealing said tube in the supply-pipe and means for regulating the by-pass, substantially as described. 105

3. In combination with a service-pipe, a gas-mixing tube projecting into said pipe and revolvably seated therein and provided with a by-pass opening leading into the service-pipe, a shutter within the burner-pipe, means for sealing the mixing-tube in the burner-pipe, and means for turning the burner-pipe to regulate the by-pass as shown. 110

4. In combination with a service-pipe, a gas and air mixing tube projected therein and sealed within the service-pipe, said tube being provided with a by-pass opening, means for regulating the by-pass, the air-supply tube encompassing the mouth of the mixing-tube, and a gas-generator and needle-valve opposite the 115 said mixing-tube, substantially as described. 120

5. In combination with a service-pipe of a generator, a gas and air mixing pipe having its mouth fixed opposite the outlet of the generator and provided with appropriate means for varying the effective length of said mixing-pipe within the service-pipe, substantially 125 as described.

6. In a vapor-generator, a gas service-pipe, a mixing-tube discharging into said pipe and 130

having a fixed mouth, a vapor-injector for entraining air into the mouth of said tube, and means for discharging the gas from said tube into said pipe at different points in said pipe, substantially as described.

7. In combination with a generator and a needle-valve controlling the outlet, of a service-pipe, a mixing-tube projecting therein composed of two sections each provided with a by-pass, one section being fixed in said pipe and the opposite section being revolubly

mounted in said pipe and provided with an open end opposite the needle-valve and means for regulating the by-pass, substantially as described.

In testimony whereof I have hereunto set my hand.

JOSEPH STUBBERS.
